UNITED STATES PATENT OFFICE

JAMES S. TAYLOR AND JAMES C. SMITH, OF TULSA, OKLAHOMA, ASSIGNEES OF ONE-HALF TO IVERSON TOOL COMPANY, OF TULSA, OKLAHOMA, A CORPORATION OF OKLAHOMA

PUMP

Application filed November 13, 1930. Serial No. 495,389.

Our invention relates to pumps and more particularly to improvements in devices of that character used in pumping oil wells and the like.

5 The principal object of our invention is to embody means in a pump of this type that will prevent the excessive wear of pump plunger cups, commonly caused by the settling of sand in the pump plunger above the cups after each period of inoperation of the pump.

Another object of the invention is to provide simple and efficient means for discharging collected sand from the pump barrel.

15 In accomplishing these and other objects of our invention we have provided details of structure, the preferred form of which is shown in the accompanying drawings, wherein:

20 Fig. 1 is a central longitudinal section of a pump embodying our invention.

Fig. 2 is a view in elevation of the pump plunger and traveling valve, a packer being shown in section.

25 Fig. 3 is a view in elevation of the standing valve and anchor.

Fig. 4 is a perspective view of a lower centering spider.

30 Fig. 5 is a perspective view of an anchor support.

Referring more in detail to the drawings:

35 1 designates a pump cylinder comprising an intermediate section 2, a lower section 3 and an upper section 4, each of these sections having internally threaded ends, as indicated at 5. The upper end of the lower section is connected to the lower end of the intermediate section by an inserted coupling 6 having a tapered socket 7 serving as a standing valve seat and diverging at its lower end into a conical mouth 8. The lower end of the upper section is connected to the upper end of the working barrel by an inserted coupling 9 provided with a concentric threaded opening 10 for receiving and supporting a working barrel 11. A guide 12 in the form of a spider and having an internally threaded hub portion 13 is secured on the lower threaded end 14 of the working barrel

to insure concentric movement of the barrel in the intermediate section.

Threaded into the upper end of the upper section 4 is a reducer coupling 15 having a threaded opening 16 whereby the pump cylinder is secured to the lower end of well tubing 17 extending, as in common practice, to the upper surface of the well. A similar reducer coupling 18 is threaded into the lower end of the section 3 and a concentric opening 19 therein slidably receives the upper end of a tubing anchor 20 provided on its upper end with a coupling 21.

45 An annular series of ports 22 is formed in communication with the concentric opening 19 so that the tubing anchor may be supported by the coupling on the ribs 23 projecting between the ports, with a portion of the ports 22 exposed beyond the outer periphery of the coupling 21 for conveying sand 70 from the pump cylinder when the tubing anchor is supported by the coupling, as shown in Fig. 1.

An accurate concentric relation of the tubing anchor with the pump cylinder is further insured by studs 24 mounted radially in the coupling 21. The upper end of the coupling 21 is fitted with a packing nut 25, serving as a guide for a gas anchor 26 which extends downwardly through the tubing anchor and is connected by a coupling 27 to a tube 28 threaded into the lower end of a standing valve assembly 29.

55 The standing valve assembly used in the present pump structure is of well known construction including a tapered seat 30 for engaging the seat 7 of the inserted coupling 6, and cups 31 for directing flow of fluid from the well into the hollow plunger whereon the valve cups are mounted. The upper end of the standing valve assembly comprises a valve cage 32 provided with the usual valve ball 33 and terminating at its upper end in a shank 34 which is formed longer than in ordinary practice and is provided with a cross pin 35 for a purpose presently described.

60 Various forms of pump plungers may be employed in the present device but the preferred form comprises a plunger 36 including a shaft 37 whereon are mounted a series of

cups 38 spaced by collars 39 and retained in assembled condition on the shaft by a nut 40 threaded on the lower end of the shaft. A second nut commonly used in connection with the nut 40 is replaced by a hook member 41 having a threaded socket 42 in its upper end for engaging the shaft and having a pair of depending fingers 43 provided with hook portions 44 to cooperate with the cross pin 35 of the standing valve cage when the cup plunger is lowered sufficiently into the working barrel, as when withdrawing the standing valve from the pump.

Threaded on the upper end of the shaft 37 is a traveling valve cage 45 retaining the usual ball valve 46 and having a threaded socket 47 in its upper end for receiving the lower threaded end 48 of a connecting rod 49 which is slidably mounted in a packer 50. Formed near the upper end of the rod 49 is an annular shoulder 51 spaced slightly from a head 52 provided on the rod adjacent its outer threaded end 53. Engaging the threaded end 53 is a sucker rod section 54 extending upwardly to the reciprocating mechanism at the upper end of the well for lowering and elevating the pump plunger in the working barrel.

The packer 50 includes a cylindrical housing 55 having an inner chamber 56 terminating in a tapered seat 57 for receiving packing material 58 urged into the chamber by a gland 59. Formed on the lower end of the packer housing is a reduced tubular shank 60 for receiving a pair of cups 61 spaced by a cup ring 62 and retained on the shank by a nut 63 and a lock nut 64.

Attention is called to the packer housing which is slightly greater in diameter than the internal diameter of the working barrel so that entrance of the packer into the working barrel will be limited, the cups 61 serving to frictionally engage the working barrel, thereby preventing retraction of the packer from the working barrel under ordinary conditions.

By providing the packer in the upper end of the working barrel, liquid pumped from the well cannot pass upwardly through the barrel and into the tubing but is bypassed as now described.

Provided near the upper end of the barrel, but below the coupling 9, are annular series of ports 65, and formed in said coupling around its concentric opening 10 are ports 66, so that fluid elevated by the pump plunger passes from the working barrel through the ports 65 and upwardly through the ports in the coupling.

In this manner, the sand carried by the oil in suspension and settling in the oil when pumping is discontinued, will be prevented from accumulating on the cups of the plunger.

Assuming a pump and working barrel cyl-

inder to be constructed and assembled as described the procedure for inserting a pump plunger into the well would be as follows:

With the pump plunger, standing valve assembly and gas anchor connected as shown in Fig. 1, the combined members are lowered into the well with the gas anchor extending downwardly.

As the connected parts are lowered into the well the gas anchor will enter the collar 21, and the standing valve assembly will be seated in the inserted coupling 6. Simultaneously the packer cups will enter the coupling 9 and the packer housing comes to rest on the upper edge of the working barrel.

Lowering of the pump plunger is then continued to permit disengagement of the hooks 44 from the transverse pin 35, this disengagement being effected by a slight rotation of the pump plunger in a clockwise direction, as will be evident from Fig. 1.

The assembled pump is now ready for operation and, upon reciprocation of the sucker rods, the pump plunger is moved upwardly and downwardly in the working barrel. As it moves upwardly liquid is drawn from the well through the standing valve, and upon downward movement of the pump plunger the liquid passes through the plunger and traveling valve, being restricted from return flow into the well by the ball 46 of the traveling valve.

The following up-stroke of the pump plunger carries the fluid upwardly in the working barrel, but due to the packer 55 in the upper end thereof the fluid must pass from the working barrel through the series of ports 65 provided in the working barrel immediately below the inserted coupling 9.

When the chamber between the working barrel and pump cylinder has become filled with oil a continued operation of the pump will force the liquid upwardly through the ports 66 in the coupling 9 and upwardly through the well tubing to a point of discharge at the top of the well.

Since fluid in the well usually carries a considerable amount of sand in suspension it is obvious that upon discontinuing operation of the pump the sand contained in the oil standing in the tubing will settle downwardly and in pumps of ordinary construction will fill the cavity surrounding the cups of the pump plunger. However, with our present construction the sand will be forced to settle downwardly through the ports in the upper inserted coupling and will come to rest on the upper face of the lower inserted coupling, thus preventing accumulation of sand on the pump plunger cups.

As a result the wear on the cups will be greatly decreased and replacement thereof will rarely be necessary. If it is desired to remove the sand accumulated on the lower coupling it is merely necessary to lower the

well tubing until the tubing anchor comes to rest on the bottom of the well. By continuing the downward movement of the tubing the lower fitting 18 slides downwardly 5 over the tubing anchor, the coupling 27 of the gas anchor comes to rest on the packing nut 25 and the standing valve assembly is elevated from its seat 7.

Fluid standing in the pump cylinder 10 around the working barrel is then free to flow downwardly in the well through the lower coupling and carries with it the sand collected on the upper surface of the coupling, the sand and fluid escaping through 15 ports 22 extending beyond the coupling 21 as previously described.

When it becomes necessary to remove the pump plunger from the working barrel it is elevated until the traveling valve engages 20 the packer and dislodges the packer cups from the working barrel whereupon the plunger and packer may be readily removed from the well.

Should it be desired to also remove the 25 standing valve and gas anchor the plunger is first lowered and attached to the standing valve by a slight anti-clockwise rotation of the pump plunger to engage the hooks 44 with the transverse pin 35 of the standing 30 valve.

What we claim and desire to secure by Letters Patent is:

1. In a pump of the character described including a cylinder, a working barrel in the cylinder, means for spacing the barrel from the cylinder having bypass ports, a pump plunger in the barrel including a connecting rod, a packer on the rod and engaging the barrel, said barrel having an outlet below 35 the packer, stop means on the rod engageable with said packer for forcing the packer into engagement with said barrel, and means for reciprocating the pump plunger to deliver fluid from said outlet and through the bypass ports.

2. In a pump of the character described, a cylinder comprising separate sections, an inserted coupling for connecting said sections and having a concentric opening and bypass 50 ports surrounding the opening, a working barrel in the cylinder threaded in said concentric opening and having an outlet below the coupling, a pump plunger in the barrel including a connecting rod, a packer on the 55 rod and engaging the barrel, means on the packer for limiting its downward movement into the barrel, and means for reciprocating the pump plunger to deliver fluid from said outlet and through the bypass ports.

3. In a pump of the character described, a cylinder comprising end sections and an intermediate section, a coupling for connecting the intermediate and upper sections and having a concentric opening and bypass ports, a 65 coupling for connecting the intermediate

and lower sections and having a seat, a working barrel in the cylinder having its upper end threaded in said concentric opening and having outlet ports below the first-named coupling, a pump plunger in the upper end of the barrel including a connecting rod, a packer on the rod and engaging the barrel, a standing valve assembly extending into the lower end of the barrel and adapted to rest on said seat, and means for reciprocating 70 the pump plunger to deliver fluid from said outlet ports and through the bypass ports.

4. In a pump of the character described, a cylinder, a working barrel in the cylinder, upper and lower spacing means for spacing the barrel from the cylinder and having bypass ports, a pump plunger in the barrel including a connecting rod, a packer on the rod comprising a tubular body having a reduced neck portion, cups and spacers on the neck, 80 means for securing the cup and spacers on said neck, a packing gland in said body portion for urging packing around the connecting rod, said barrel having outlet ports below the packer, and means connected to the rod for reciprocating the pump plunger to deliver fluid from said outlet and through the bypass ports of said upper spacing means.

5. In a pump of the character described, a cylinder comprising end sections and an intermediate section, a coupling for connecting the intermediate and upper sections and having a concentric opening and bypass ports, a coupling for connecting the intermediate and lower sections and having a seat, a working barrel in the cylinder engaging said concentric opening and having outlet ports below the first-named coupling, a pump plunger in the upper end of the barrel including a connecting rod, a packer on the rod and engaging the barrel, a standing valve assembly extending into the lower end of the barrel and adapted to rest on said seat, and means on the lower end of the plunger and on the upper end of the standing valve for effecting a connection of the parts upon rotation of the plunger on the standing valve.

6. In a pump of the character described including a cylinder, a working barrel, a spider secured to the lower end of the barrel for guiding said barrel in the cylinder, means secured to the upper end of the barrel for concentrically spacing the barrel from the cylinder and having by-pass ports, a pump plunger in the barrel including a connecting rod, a packer on the rod and engaging the barrel, said barrel having an outlet below the packer, and means for reciprocating the pump plunger to deliver fluid from said outlet and through the by-pass ports.

7. In a pump of the character described including a cylinder, a working barrel in the cylinder, means secured to the cylinder and to the upper end of the working barrel for supporting the barrel in said cylinder, said

means having by-pass ports, a pump plunger in the barrel including a connecting rod, a packer on the rod and engaging the barrel, said barrel having an outlet below the packer,

5 and means for reciprocating the pump plunger to deliver fluid from said outlet and through the by-pass ports.

8. In a pump of the character described including a cylinder, a working barrel in the cylinder, means secured to the cylinder and to the upper end of the working barrel for supporting the barrel in said cylinder, said means having by-pass ports, a pump plunger in the barrel including a connecting rod, a

10 packer on the rod and engaging the barrel, stop means on the rod engageable with said packer for forcing the packer into engagement with said barrel, said barrel having an outlet below the packer, and means for reciprocating the pump plunger to deliver fluid from said outlet and through the by-pass ports.

15 9. In a pump of the character described including a cylinder, a working barrel in the cylinder, means secured to the cylinder and to the upper end of the working barrel for supporting the barrel in said cylinder, said means having by-pass ports, a guide secured to the lower end of the barrel and slidably

20 engaging the cylinder, a pump plunger in the barrel including a connecting rod, a packer on the rod and engaging the barrel, stop means on the rod engageable with said packer for forcing the packer into engagement with said barrel, said barrel having an outlet below the packer, and means for reciprocating the pump plunger to deliver fluid from said outlet and through the by-pass ports.

25 10. In testimony whereof we affix our signatures.

JAMES S. TAYLOR.
JAMES C. SMITH.
